Primary Examiner—Philip S. Hyder

[57] CLAIM

The ornamental design for a rowing exerciser, as shown and described.

DESCRIPTION

FIG. 1 is a perspective view of a rowing exerciser according to our design;

FIG. 2 is a front elevational view thereof, wherein the rear view is a mirror image of FIG. 2;

FIG. 3 is a left side elevational view thereof;

FIG. 4 is a right side elevational view thereof;

FIG. 5 is a top plan view thereof; and,

FIG. 6 is a bottom plan view thereof.
